CLAIM

The ornamental design for an electronic device with transitional graphical user interface, as shown and described.

DESCRIPTION

1. Electronic device with transitional graphical user interface

1.1 : Front

1.2 : Front

1.3 : Front

The outer perimeter shown in broken lines illustrates an electronic device and forms no part of the claimed design; the remaining broken lines in the figures illustrate portions of the graphical user interface that form no part of the claimed design; the appearance of the transitional image sequentially transitions between the images shown in reproductions 1.1 through 1.3; the process or period in which an image transitions to another image forms no part of the claimed design.
